UNITED STATES PATENT OFFICE.

WILLIAM HENRY HERBST, OF DEDHAM, MASSACHUSETTS.

MEANS FOR CLEANING AND TURNING BAGS.

1,104,668.

Specification of Letters Patent. Patented July 21, 1914.

Application filed August 29, 1912. Serial No. 717,785.

To all whom it may concern:

Be it known that I, WILLIAM H. HERBST, citizen of the United States, residing at Dedham, in the county of Norfolk and State of Massachusetts, have invented certain new and useful Improvements in Means for Cleaning and Turning Bags; and I do hereby declare the following to be a full, clear, and exact description of the invention, such as will enable others skilled in the art to which it appertains to make and use the same.

This invention relates to means for cleaning and turning bags.

The object is to provide a device of simple construction which will do the work of more elaborate machines, which shall be efficient in performing the turning operation, and which will then thoroughly clean the bag, the air having access to all portions of the latter while it is being held by suction in an expanded form against walls of screen-like formation.

With these and other objects in view, the invention consists in the novel construction hereinafter set forth and claimed, and illustrated in the accompanying drawings, in which—

Figure 1 is a view of the construction in side elevation, with parts in section. Figs. 2 and 3 show details of the device.

In carrying out my invention, I employ a tubular member 10 which has connection with an exhaust fan 15 mounted on any suitable supporting structure 16. The duct constituting the dust outlet from the fan is shown at 17.

It is obvious that the member 10, which will be termed a suction pipe, may be located in any manner desired, but it is found convenient to have it depend vertically, and terminate at a convenient distance above the floor, so that an operator may readily place the bags to be turned and cleaned, at the mouth of the pipe.

Especial importance is attached to the means for retaining the bag in a suitable position to be cleaned after it has been placed at the mouth of the pipe and turned by suction while the edges are being held by the operator against the edge of the pipe.

A cylindrical screen of suitable mesh is placed within pipe 10, and provides an annular air space 18 between the two members, this air space having direct communication with a larger air chamber 19 beyond the end

of the screen, the latter being indicated by the number 20. In order to hold the screen suitably spaced from pipe 10, spacing members 21 are provided, of such character as to admit of the free passage of the air. It will be noticed that the suction is direct between all portions of the annular air space 18 and the exhaust device.

In order that the screen may be removed for any purpose, as for instance to permit the substitution of a screen of another size, tube 10 is provided with a telescoping collar member 22 which is secured in position by devices 23. This collar is made to taper and is provided with a rolled edge 24.

Screen member 20 is secured to collar 22, so that when the latter is removed the screen may be withdrawn at the same time.

It will be observed that the main portion 75 of pipe 10 is of uniform cross section and that there are no obstructions to engage the screen spacing members when they pass the mouth of the pipe.

The end portion 25 of screen 20 is of larger 80 mesh and retains the bag, preventing it from being drawn into the fan casing. Screens of different mesh and of different cross section may be employed.

The device contains no valves, nor any 85 moving parts other than the fan, the latter operating continuously to produce constant suction sufficient for the purpose, and for whipping the sides of the bag against the screen.

If the bag is right side out at the beginning, it is first turned, then cleaned, the cleaning operation beginning during the turning operation, and is then again turned to bring the bag to the right side. In the 95 event that the user has turned the bag in emptying it, the first turning in the machine leaves the bag right side out, and it is cleaned in that position, and while being turned.

What I claim as new and desire to secure 100 by Letters Patent, is:

1. In a bag cleaning device, a tubular casing, means for producing suction therein, and tubular means for preventing a bag held in the casing by suction from passing through the casing and from contacting with the walls of the casing, an air chamber being formed by said means between the latter and the casing.

2. In a bag cleaning device, a duct, means 110 for exhausting air therefrom, a tubular cage-like member within the duct and spaced

- from the walls thereof, to form an annular air chamber between the cage member and the walls of the duct, one end of said member being open.
5. 3. In a bag cleaning device, a duct, means for partially exhausting air therefrom, a member for receiving a bag detachable from the end of the duct, and a screen constituting a receptacle connected with said member and projecting into the duct.
4. In a bag cleaning device, a duct, means for partially exhausting air therefrom, a tubular member within the duct and provided with openings for the passage of air, and means for spacing the said member and the sides of a bag received thereby from the walls of the duct, said means last mentioned being slidable with reference to the walls.
5. In a bag cleaning device, a duct, an exhaust fan connected therewith, a screen member extending transversely of the duct at a distance from the mouth, a detachable collar connected with the end of the duct, for receiving a bag, a tubular cage-like member connected with the collar and extending to the aforesaid screen, and means for spacing the member and the sides of a bag received thereby from the walls of the duct and having slidable connection with the latter.

In testimony whereof I affix my signature in presence of two witnesses:

WILLIAM HENRY HERBST.
